UNITED STATES PATENT OFFICE.

CHARLES THOMAS MASON, OF SUMTER, SOUTH CAROLINA, ASSIGNEE, BY MESNE ASSIGNMENTS, TO SPLITDORE ELECTRICAL COMPANY, OF NEWARK, NEW JERSEY, A CORPORATION OF NEW JERSEY.

IGNITION DEVICE FOR INTERNAL-COMBUSTION ENGINES.

1,183,096.

Specification of Letters Patent.

Patented May 16, 1916.

Application filed January 23, 1912. Serial No. 672,921.

To all whom it may concern:

Be it known that I, CHARLES THOMAS MASON, a citizen of the United States, residing at Sumter, in the county of Sumter and 5 State of South Carolina, have invented certain new and useful Improvements in Ignition Devices for Internal-Combustion Engines, of which the following is a specification, reference being had to the accompanying drawing.

My invention relates to alternating current dynamos such as used with internal combustion engines for ignition purposes, and more particularly to dynamos used with 15 engines where the time of ignition is varied.

The objects of my invention are to provide a device of this nature whereby the intensity of the spark is the same whether the engine ignition is advanced or retarded. I also 20 provide improved methods of oiling, of adjusting the position of the dynamo as the spark is advanced and retarded, of timing the armature of the dynamo in relation to the engine, and an improved terminal arrangement.

While alternating current dynamos are used with engines having variable ignition, they usually have the objection of producing a weak spark in a retarded position if 30 properly timed to give the maximum spark in the advanced position. In other words the spark is not uniform throughout the entire range from extreme retard to full advance. My invention avoids this difficulty 35 and provides a better structure embodying the improvements hereinbefore mentioned.

Figure 1 is a side view of a dynamo embodying my invention. Fig. 2 is an end view of the dynamo. Fig. 3 is an end view 40 partly in section. Fig. 4 is a view looking down on top of the machine slightly modified showing the timing means I employ. Fig. 5 is a sectional view through the end plate and terminal I employ. Fig. 6 is an 45 external end view of the terminal.

The same letters and figures of reference denote the same parts wherever they are shown.

For the sake of illustration I show a type 50 of dynamo commonly known as a magneto, this being of the permanent magnet type, but it is obvious that any type of field magnets may be employed, and it will be fur-

ther understood that the armature design and construction may be of any suitable character.

The reference character 1 denotes the permanent magnets, in the magnetic field of which is placed the armature, the shaft of which is shown at 2. The armature shaft is supported by suitable end plates 3 and 4 usually constructed from a non-magnetic metal. The end plates have shoulders which are carried in supports 5 and 6, in which the magnet structure as a whole is free to turn. 65 These supports may be made of non-magnetic material, in which case they are connected by suitable members 7, 8, 9 and 10 of magnetic material; or the connecting members may be non-magnetic and the supports magnetic, the idea being to eliminate as much as possible magnetic leakage through the supports and connecting members, which would be very great if all of them were constructed from magnetic metals.

From the foregoing it will be noted that the armature is carried on end plates one of which is shown at 31 Fig. 5, into which the shafts are riveted and that this armature is free to rotate in bearings in the magnet structure end plates 3 and 4. It will also be noted that the magnet structure carrying the revoluble armature is supported in the cradle formed by the supports 5 and 6, so that the entire machine consists of the following main parts, to wit: a stationary cradle supporting a movable magnet structure which in turn supports a revoluble armature.

Attached to any portion of the dynamo, for instance to the top of same, as shown in Fig. 2, I provide the piece 11 and the connecting rod 12, by means of which the magnet structure may be tilted in any position. The rod 12 may be connected to the spark mechanism on an engine having a make and break igniter so that the position of the dynamo is altered in unison with the igniter mechanism.

In one or both of the supports 5 and 6 I provide a recess in which is placed the block 13 of any suitable material, against which bears the screw or other adjusting means 14, whereby a frictional resistance 105 can be established between the support 6

and the end plate 4. This arrangement eliminates the necessity of a very accurate fitting of the parts, and yet insures the proper adjustment between them, which adjustment may be readily changed to compensate for wear.

The supports 5 and 6 are provided with suitable oil holes 15, communicating with a pocket 16 in the end plate of such proportions that oil placed in 15 will always find its way to the bearing for shaft 2 regardless of the position of the magnet structure relative to its supports. This same oil serves to lubricate the shoulders of the end plates 15 where they rest in the supports.

In the feet of the supports are placed suitable holes 29 and 30 whereby the supports may be bolted to a suitable support and geared to the engine by a suitable gear 20 placed on shaft 2. When so mounted it is evident the magnet structure may be moved about the shaft 2 as a center, thereby altering the position of the dynamo field in relation to the timing of the engine without 25 altering the position of the armature in relation to the timing of the engine, consequently the spark is produced at the peak of the wave and is always of the same intensity regardless of the position of the dynamo field, as the pole pieces are altered in their 30 position in regard to the armature so as to keep the dynamo properly timed with the engine.

To facilitate timing the dynamo with the engine, the shoulder 17 on the end plate 3 is provided with suitable marks such as R and L, and a disk 18 is secured to the armature shaft, this disk having one or more notches N therein. The notch N shows the armature position, marks R and L the "peak" positions in relation to the pole pieces for right and left hand rotation. Now supposing the rotation to be right hand and the engine to be equipped with a make and 40 break igniter, the magnet structure should be placed in the starting position shown by the heavy lines Fig. 2, and the engine turned over slowly until the igniter snaps, then with the usual driving gear loose on the armature shaft turn the setting disk 18 until N is in a line with R (if the rotation were 45 left-handed, the magnet structure would be tilted in the opposite direction and N would be set to L). The driving gear is now positively secured to shaft 2 and the dynamo connected to the igniter by a wire from the insulated terminal 19, the circuit being completed through the engine frame and the frame of the dynamo as one side of the armature winding is connected to the dynamo 50 frame.

As the magnet structure is moved it is obvious that if the terminal for the insulated side of the armature winding was 55 mounted on the dynamo proper it would

also move, and there would be danger of breaking the connecting wire. I obviate this by associating the terminal with the stationary support 6 in such a manner that it is stationary at all times.

The terminal piece 19 is mounted in an insulating support 20 in which it is held by any suitable means, such as the clamp 21; positioned in 19 are the conducting brushes 22 and 23 which bear against the stud 24 75 mounted in the insulating bushing 25 carried in the hollow shaft 26 of the dynamo armature. The inner end of 24 carries a terminal 27 to which is attached one end of the armature winding, the other end of 80 same being grounded on the frame.

To prevent oil from interfering with the electrical contact between the brushes and the stud 24, the oil drain 28 is provided, and a free open space between the bearing of the 85 armature shaft 26 and the brushes is arranged into which any oil escaping from the bearing may drain.

In operation, to start an engine equipped with this dynamo and with a make and break igniter the dynamo field and igniter should be placed in the "starting" or retarded position and the engine started in the ordinary manner, after which the spark may be advanced by moving the igniter and 90 dynamo field to the "running" position. When starting the dynamo field being tipped in the direction in which the armature is rotating and timed definitely with the engine, the pole pieces are in proper relation to the armature to secure the peak of the current wave when the igniter snaps. Now were the igniter advanced and the 95 dynamo field remained stationary, the position of the armature to the pole pieces would be changed and the peak of the wave would no longer be utilized when the igniter operated, but by moving the dynamo field opposite to the direction in which the armature is rotating the relation of the pole pieces to the armature is changed and coincides properly with the timing of the igniter, and enables the peak of the current 100 wave to be utilized at the proper instant.

I claim:—

1. In an ignition dynamo, an armature having end plates, co-axial shafts secured to said end plates, a magnet structure forming a housing for said armature, end plates on said housing forming supports for said shafts, outwardly projecting shoulders on said end plates, a support for said shoulders, a circuit terminal carried by said support, a circuit terminal carried by one of said shafts, and connecting means between 115 said circuit terminals.

2. In an ignition dynamo, a revoluble armature core adapted to carry a winding, heads attached to said core, shafts attached to said heads, a field structure, end plates 120

attached to said field structure and forming supports for said shafts, and a supporting cradle for said end plates wherein said plates and the parts they carry are movable, 5 said cradle comprising end members connected by rods, substantially as described.

3. In an ignition dynamo, pole pieces, an armature, a shaft therefor, an insulated contact piece forming a flat end on said shaft, relatively rotatable supports for said shaft forming end plates for the dynamo pole pieces, fixed supports for said rotatable supports, whereby the latter are freely movable about the armature axis, an insulated 10 terminal carried by said last mentioned supports, and conducting means between said terminal and contact piece.

4. In an ignition dynamo, pole pieces, an armature, an insulated contact piece forming a flat end on the shaft of said armature, relatively rotatable supports for said shaft forming end plates for the dynamo pole pieces, fixed supports for said rotatable supports whereby the latter are freely movable 25 about the armature axis, an insulated terminal carried by a split collar on one of the fixed supports, and conducting means between said terminal and contact piece.

5. In an ignition dynamo, stationary supports, a field structure carried thereby, a rotatable armature, and a two part timing indicator having one part in fixed relation to said field structure and the other part attached to said armature whereby the relative adjustment of said armature to said field may be accurately determined by open 30 visual indication without removing or pro-

curing access to any of the internal parts of the device.

6. In an ignition dynamo, stationary supports forming a base, a field structure carried thereby and movable therein, a rotatable armature in working relation to said field structure and having a shaft extending outside said supports, and a two part timing 40 indicator, one part in fixed relation to said field structure and external said supports, and the other part attached to said shaft and movable therewith for timing purposes, substantially as described. 50

7. In an ignition dynamo, an armature having an end plate, a hollow shaft secured to said plate, an insulated contact piece in said shaft, a bearing plate supporting said shaft, an outwardly projecting shoulder on said bearing plate, a supporting member engaging said shoulder, an insulated terminal carried by said supporting member, and connecting means between said terminal and said contact piece. 55

8. In an ignition dynamo, a cradle comprising two end member forming supports, a magnet structure carried in said supports and rotatable therein, an armature carried in said magnet structure and means for clamping said magnet structure in said cradle, substantially as described. 60

In testimony whereof I hereunto affix my signature in the presence of two witnesses.
